UNITED STATES PATENT OFFICE.

CHARLES V. JESSEE, OF IVAN, TEXAS.

SHEARS.

Application filed November 25, 1921. Serial No. 517,743.

To all whom it may concern:

Be it known that I, CHARLES V. JESSEE, a citizen of the United States, residing at Ivan, in the county of Stephens and State 5 of Texas, have invented certain new and useful Improvements in Shears, of which the following is a specification.

This invention relates to shears and has for an object to provide a new and improved 10 bearing for shears of various types and sizes and for various purposes.

A further object of the invention is to provide a roller bearing for shears with improved means for maintaining the bearing 15 in organized condition.

With these and other objects in view, the invention comprises certain novel units, parts, elements, combinations, arrangements, 20 functions and mechanical movements as disclosed in the drawing, together with equivalents thereof, as will be hereinafter more fully described and claimed.

In the drawings:

Fig. 1 is a view in side elevation of a 25 pair of conventional domestic scissors.

Fig. 2 is a view of said scissors in edge elevation.

Fig. 3 is a fragmentary view of one of the blades showing the roller bearing in 30 end elevation.

Fig. 4 is a transverse section taken through the pivoted connection between the blades.

Fig. 5 is a further detailed sectional view 35 showing more fully the roller bearings.

Like characters of reference indicate corresponding parts throughout the several views.

The improved bearing, which forms the 40 subject matter of this application, is adapted to be associated with shears of various types and sizes and for various purposes. As shown in the drawing, a pair of domestic scissors is disclosed comprising the usual and ordinary blades A and B and pintle pin C of substantially the usual and ordinary type with their ordinary and accustomed handle features. It is to be understood that the invention is in no way 45 limited to the specific type of shears shown, such type being shown wholly and purely by way of illustration.

The blades A and B are each provided 50 with an opening 10 concentric with, and larger than the pintle C and a plurality

of rollers 11 is introduced into the resultant annular space between the margins of such perforation and such pintle, as shown more particularly at Fig. 3.

The length of these rollers 11 correspond 60 to the thickness of the blades, as shown more particularly at Fig. 2, and a ring or race 12 is interposed between the proximate ends of the rollers. The rollers are further held in position against displacement by external 65 covering members, here shown as plates 13 and 14, which are engaged respectively under the nut 15 and the head 16 of the pintle. These keepers 13 and 14 may be in the form of rings or races large enough to cover 70 the perforation 10 of the blades, but preferably are made as elongated strips, as shown at Figs. 1 and 2, and rigidly secured to the handle parts of the blades preferably, though not necessarily, by welding, so that 75 between the blade B and its keeper 13, space is provided for the reception of the blade A, while between the blade A and its keeper 14, space is provided for the reception of 80 the blade B. By this means the keeper 85 13 of the blade B operates in unison with the blade A and the keeper 14 of the blade A operates in unison with the blade B, and maintain the rollers against longitudinal displacement outwardly, their inner ends being engaged, as stated, by the washer 12.

In assembling it is obvious that the rollers will be placed in position within the perforations of the blades and the blades then crossed in operative position and the 90 pintle inserted, the nut 15 being screwed down to secure the necessary or desired cutting tension.

I claim:

1. Shears of the type described, comprising crossed blades, a pintle, a circular arrangement of rollers, said blades having enlarged perforations receiving said pintle and also adapted to receive the circular arrangement of rollers, said rollers encompassing 95 said pintle, keepers fixed to the blades, the free or remote ends of said keepers adapted to form closures for the terminals of said pintle receiving perforation, and a washer 100 arranged between said blades and upon said pintle intermediate the adjacent ends of the rollers and engaged by the rollers.

2. A shear comprising crossed blades and 105 a pintle, said blades being provided with perforations larger than and surrounding 110

the pindle, a washer interposed between the blades and positioned upon the pindle, rollers inserted in the annular spaces about the pindle within the perforations of the blades and engaging the washer and a keeper carried by the handle of each of said blades bearing against the exterior of the other

blade and cooperating with the washer to prevent displacement of the rollers from the perforations.

10

In testimony whereof I affix my signature.

CHARLES V. JESSEE.
